(57) **CLAIM**

The ornamental design for a pair of handles for a microwave container cover, as shown and described.

DESCRIPTION

FIG. 1 is a top, side and front perspective view of a pair of handles for a microwave container cover showing my new design;

FIG. 2 is a bottom, side and rear perspective view thereof;

FIG. 3 is a front elevation view thereof;

FIG. 4 is a rear elevation view thereof;

FIG. 5 is a right side elevation view, the left side elevation being identical thereto;

FIG. 6 is a top plan view thereof; and,

FIG. 7 is a bottom plan view thereof.

The broken lines showing environmental structure is for illustrative purposes only and forms no part of the claimed design.
